CLAIM

The ornamental design for a dispenser with laterally-actuated dispensing valve, as shown and described.

DESCRIPTION

FIG. 1 is a top and left perspective view of a first embodiment of a dispenser with laterally-actuated dispensing valve of the present invention;

FIG. 2 is a left side elevational view of the dispenser with laterally-actuated dispensing valve of FIG. 1;

FIG. 3 is a top elevational view of the dispenser with laterally-actuated dispensing valve of FIG. 1;

FIG. 4 is a right side elevational view of the dispenser with laterally-actuated dispensing valve of FIG. 1;

FIG. 5 is a bottom elevational view of the dispenser with laterally-actuated dispensing valve of FIG. 1;

FIG. 6 is a front end elevational view of the dispenser with laterally-actuated dispensing valve of FIG. 1;

FIG. 7 is a rear end elevational view of the dispenser with laterally-actuated dispensing valve of FIG. 1;

FIG. 8 is a top and left perspective view of a second embodiment of a dispenser with laterally-actuated dispensing valve of the present invention;

FIG. 9 is a left side elevational view of the dispenser with laterally-actuated dispensing valve of FIG. 8;

FIG. 10 is a top elevational view of the dispenser with laterally-actuated dispensing valve of FIG. 8;

FIG. 11 is a right side elevational view of the dispenser with laterally-actuated dispensing valve of FIG. 8;

FIG. 12 is a bottom elevational view of the dispenser with laterally-actuated dispensing valve of FIG. 8;

FIG. 13 is a front end elevational view of the dispenser with laterally-actuated dispensing valve of FIG. 8; and,

FIG. 14 is a rear end elevational view of the dispenser with laterally-actuated dispensing valve of FIG. 8.

The broken lines in the figures show structure or boundaries that are not part of the claimed design, but rather show the environment in which the design is associated, or show portions of the article in which the design is embodied or applied to that are not considered part of the claimed design.
